YARN CLEARER

Burt A. Peterson, Rockford, Ill., assignor to Barber-Colman Company, Rockford, Ill., a corporation of Illinois

Application July 10, 1936, Serial No. 89,915

7 Claims. (Cl. 28—68)

The invention pertains to yarn clearers for use in connection with winders or spoolers, and the general object of the invention is to provide an improved yarn clearing device which is capable 5 of effectually clearing the thread or yarn of particles of fiber, leaf and other extraneous matter, and which is operative automatically to effect breakage of the thread or yarn to prevent passage of gouts or other enlargement onto the 10 cheese being wound.

Another object is to provide a yarn clearing device having a highly sensitive means for gripping the yarn to break the same in order to prevent passage of a gout, which is adjustable to 15 vary the degree of sensitivity according to the kind and size of the yarn being wound.

Another object is to provide a yarn clearing device of improved construction which is adjustable for different sizes of yarn, and which is 20 adapted for automatic operation by the winder mechanism to release the yarn in the event that it has been caught or gripped by the operation of the device in preventing the attempted passage of a gout or other enlargement.

25 The objects of the invention thus generally stated together with other and ancillary advantages are attained by the construction and arrangement set forth by way of illustration in the accompanying drawing, in which:

30 Figure 1 is a fragmentary side elevational view of the improved yarn clearing device shown in its relation to the winder mechanism.

Fig. 2 is an enlarged end elevational view of 35 the device as shown in Fig. 1 and illustrating the manner in which it is mounted on the framework of the winder mechanism, which framework is shown in section.

Fig. 3 is a front elevational view of the device.

Fig. 4 is a fragmentary vertical sectional view 40 taken approximately in the plane of line 4—4 of Fig. 3.

Fig. 5 is a fragmentary sectional view on an enlarged scale, taken approximately in the plane of line 5—5 of Fig. 3 and illustrating the operation 45 of the device in severing the yarn as an incident to the attempted passage of an enlargement thereon.

The improved yarn clearer is adapted for use 50 in various forms of winders or spoolers, but is particularly adapted for use in connection with an automatic winder of the type disclosed in the Colman Patents Nos. 1,267,977 and 1,274,386, granted May 28, 1918 and August 6, 1918, respectively. In Fig. 1 I have shown the general 55 relationship of the parts. 7 designates a bobbin

from which a thread or yarn 8 passes through the yarn clearer generally designated 9, and from thence partially around a winding drum 10 and onto a cheese 11.

The device 9 comprises a stationary grip plate 5 12, preferably providing a smooth flat surface over which the yarn passes; and a sensitive gripping element in the form of a blade 13 inclined toward the plate 12 in the direction of approach of the yarn, and swingably supported 10 with its gripping edge spaced from the guiding surface of the plate 12 a distance determined by the thickness of the yarn.

As herein shown, the plate 12 is formed by a 15 vertical leg of a horizontal angle bar 14 having one end suitably secured to the base 15 of a generally U-shaped frame 16 having two laterally spaced standards 17. The other end of said bar projects laterally to one side of said frame, which similarly supports a plurality of stationary yarn 20 guiding pins 18 in vertically spaced relation, four such pins being herein shown. The three upper pins are adapted to cooperate with two prongs 19 of a thread detector forming part of the winder mechanism, and the two lower pins serve 25 to guide the yarn for passage over the smooth surface of the plate 12 and between said surface and the lower free edge of the blade 13 which is inclined downwardly toward the plate.

The supporting structure further includes as 30 herein shown, two interfitting U-shaped plates 20 and 21 (Fig. 2) suitably mounted on a stationary member 22 of the winder and carrying the U-shaped frame 16, the base member 15 of which is secured to the upper plate 20 at one end 35 and rearwardly thereof. The opposite ends of said plates 20 and 21 have extensions 20^a and 21^a projecting laterally beneath the lowermost pin 18 and respectively providing opposed vertically spaced thread guiding surfaces 23 and 24, 40 the lower one of which is formed by the rear end of a forwardly opening slot in the plate extension 21^a.

The means for pivotally supporting the blade 13 comprises a pair of pivot points 25 and 26 45 (Fig. 3) engaging in small recesses in the opposite side edges of the blade. In the preferred construction the blade is carried by a rock shaft 27 suitably journaled in the frame members 17 somewhat above and in rearwardly spaced relation to the plate 12. One end of this shaft projects laterally from its supporting frame parallel to the angle bar 14, and this projecting end portion is cut away on its under side to form a notch 28 so as to accommodate the pivot points 25 50 55

and 28 which are mounted in the opposite ends of the notch coaxially of the shaft. As clearly shown in Fig. 5, the notch 28 opens in a generally downward direction with the bottom face thereof inclined downwardly in the direction of the plate 12.

The end of the shaft 27 opposite the notched portion supporting the blade 13 projects from the U-shaped frame 16 and carries a crank pin 10 or arm 29. The latter projects forwardly from the shaft and turning movement of the shaft in a clockwise direction (Fig. 2) is limited by a set screw 30 suitably supported in a bracket 31 on the frame member 16. Yieldably urging the crank arm 29 against the screw is a spring clip 32 (Fig. 4) made from a thin flat plate of spring steel fitted over the pins 18 between the upright standards 17 of the frame 16. The rear leg of this clip has its lower end shaped to provide a flat lip portion 33 yieldably engaging a flat side 34 formed rearwardly of the shaft 27. Preferably the lip portion 33 of the clip is disposed angularly relative to the bottom of the notch 34 so as to engage therewith below the axis of the shaft, thereby exerting a constant turning force on the shaft in a direction to hold the crank arm 29 against the screw 30.

It will be observed that the blade 13 is pivotally supported upon the shaft in a manner such as to permit free turning movement thereof through a limited extent which in the present instance is sufficient to permit movement of the lower free edge of the blade to perform its thread-gripping function in cooperation with the plate. Normally the upper rear end of the blade is yieldably held in engagement with a stop or abutment 28^a formed by the upper rear portion of the bottom of the notch 28. This position would be maintained by the action of gravity, but in the preferred embodiment I do not depend upon gravity for this purpose but employ spring means susceptible of accurate adjustment to vary the force required to swing the blade in the operation of gripping a thread or yarn. Said spring means comprises in the present instance a coiled expansion spring 35 encircling the shank of a screw 36 projecting downwardly and rearwardly in the notch 28 substantially perpendicular to the bottom thereof. The spring bears between the head 50 of the screw and a washer 37 engaging with the under side of the blade, which latter is provided with an enlarged opening 38 to permit passage of the screw without interfering with the limited rocking motion of the blade relative to the shaft. 55 It will be seen that the slot formed between the lower forward edge of the blade 13 and the rear face of the plate 12 may be varied in width according to the normal thickness of the yarn being wound, merely by changing the angular position 60 of the rock shaft 27 by means of the adjusting screw 30. As shown, the edge of the blade is in the present instance serrated, and in the normal operation the blade serves to clear the yarn of fibers and other extraneous substances. In Fig. 65 3, broken lines 8^a and 8^b indicate the range of lateral motion imparted to the yarn in the winding operation. With such motion imparted to the yarn, the serrated edge of the blade in clearing the yarn from fibers and the like is rendered 70 more effective.

The fibers thus cleared from the yarn tend to accumulate beneath the blade 13 so as to form a gout having a tendency to disengage itself from the blade and pass onto the cheese. With the 75 construction which I have provided, the blade 13

is sufficiently sensitive to respond to the abnormal force exerted on the blade by the gout in the pull of the thread, and to lift the blade, forcing its free edge against the plate 12 whereby to clamp and break the yarn. By means of the screw 36, 5 the tension of the spring 35 opposing the gripping action of the blade may be readily varied as may be desired depending upon the kind and size of the yarn which is being wound.

To release a strand of yarn gripped by the 10 blade 13 in cooperation with the plate 12, the shaft 27 may be rocked counterclockwise by depressing the crank arm 29. When the device is used in connection with an automatic winder of the type shown in Patent No. 1,267,977, the traveling mechanism of the winder is provided with a cam bar arranged to depress the crank arm. To limit rotational movement of the shaft 27 the latter has a stop pin 39 engageable with the bracket 31. 20

I claim as my invention:

1. A yarn clearer having, in combination, means providing a yarn guiding surface, a rock shaft spaced from said surface and disposed substantially perpendicular to the direction of travel of the 25 yarn, a blade having a pivotal support coaxial with the shaft and inclined in the direction of approach of the yarn, said shaft having an abutment limiting pivotal movement of the blade in a direction away from said surface, and spring means yieldably holding said blade against said abutment.

2. A yarn clearing device comprising, in combination, means providing a yarn guiding surface, a shaft mounted in spaced relation to said surface and disposed substantially horizontally to the direction of travel of the yarn, said shaft having a notch in one side thereof, pivot points mounted in said shaft in the ends of said notch, a blade mounted on said pivot points and inclined 40 in the direction of approach of the yarn with one end of the blade spaced a predetermined distance from said surface, and means including a spring acting upon the opposite end of said blade to hold it against the bottom of said notch. 45

3. A yarn clearing device comprising, in combination, means providing a yarn guiding surface, a supporting member mounted in spaced relation to said surface, said member having a notch in one side thereof, pivot points mounted in said member in the ends of said notch, a blade mounted on said pivot points and inclined in the direction of approach of the yarn with one end of the blade spaced a predetermined distance from said surface, the opposite end of said blade having an 55 opening therein, a screw anchored in the member and passing loosely through said opening, and a spring encircling said screw and yieldably holding the blade against swinging movement relative to the member. 60

4. A yarn clearing device comprising, in combination, means providing a fixed upright guiding surface over which the yarn is adapted to pass in an upward direction, a supporting member, a blade mounted on said member to turn on a horizontal axis and inclined downwardly from said axis with its lower edge normally spaced from said surface a distance corresponding to the normal thickness of the yarn, said blade being pivotally supported intermediate its edges for limited 70 rotational movement in one direction, and spring means cooperating with the upper edge portion of the blade and said supporting member for yieldably resisting movement in the opposite direction. 75

5. A yarn clearing device comprising, in com-

5 bination, means providing a yarn guiding surface, a rotatively adjustable supporting member mounted in spaced parallel relation to said surface and providing an abutment, a blade swingably mounted on said member and disposed in inclined relation to said surface with one edge portion adapted to cooperate with said surface, said blade having a part engageable with said abutment, and spring means carried solely by 10 said supporting member acting to hold said part yieldably against said abutment.

10 6. A yarn clearing device comprising in combination, means providing a yarn guiding surface, a supporting member providing an abutment, a 15 blade pivotally mounted on said supporting member and inclined in the direction of approach of the yarn with one edge portion adapted to cooperate with said surface, said blade having a part engageable with said abutment, spring

means on said supporting member acting to hold said part yieldably against said abutment, said supporting member being mounted for rotational movement, a stationary stop, and means including a spring for holding said member against said 5 stop.

7. A yarn clearing device comprising, in combination, a stationary member having a yarn guiding surface, a blade inclined relative to said surface and having one edge adapted to cooperate with said surface, means pivotally supporting the blade comprising a rock shaft, an abutment on the rock shaft for limiting pivotal movement of the blade, adjustable spring means carried solely by the rock shaft for holding the blade against 10 said abutment, and means for turning the rock shaft to vary the position of the edge of the blade relative to said yarn guiding surface. 15
